UNITED STATES PATENT OFFICE.

ELLEN WEINSTEIN, OF SAN FRANCISCO, CALIFORNIA.

LINGERIE FASTENER.

Application filed September 28, 1925. Serial No. 58,961.

To all whom it may concern:

Be it known that I, ELLEN WEINSTEIN, a citizen of the United States, residing in the city and county of San Francisco and State of California, have invented new and useful Improvements in Lingerie Fasteners, of which the following is a specification.

The present invention relates to fasteners used in holding under garments or lingerie in their proper positions with relationship to the outer dress of the wearer, without the use of other additional means.

There has been considerable difficulty experienced in the past by women wearing lingerie on which shoulder straps are attached, in maintaining the garments in their proper positions and in keeping the straps extending over the shoulders from falling therefrom. To obviate this difficulty and to eliminate the inconvenience of continually replacing the straps upon the shoulders, various means have been devised, but none of them have proven satisfactory in either convenience or operation.

My invention comprises a pair of safety pins joined together, one of which is attached to the dress of the wearer and the other of which is attached to the shoulder strap of the under garment. The connection of the dress with the shoulder strap by means of my invention, prevents the shoulder strap from falling over the shoulders and from otherwise assuming improper positions on the wearer.

An object of the present invention is to provide a fastener for lingerie or other similar garments, whereby the same may be maintained in their proper positions on the wearer.

A further object of the present invention is to provide a simple and inexpensive device for fastening an under garment to the outer garment of the wearer.

In the accompanying drawing:

Fig. 1 is a view of my invention showing the manner in which the various parts are connected to each other;

Fig. 2 is a view of my invention showing the same in another form; and Fig. 3 is a

view of my invention showing how the same is applied to the garments of the wearer.

Referring to the drawings the numeral 1, represents the body portion of an ordinary safety pin which is comprised of a sheath 2, a spring 3 and a pointed end 4. The present invention comprises two ordinary safety pins, *a* and *b*, having the parts above designated, with the point of one of the safety pins sharpened so as to easily perforate cloth, and the point 5, of the other safety pin blunted, so as to avoid the pricking of the skin of the wearer. The body portions 1 of the safety pins, as shown in Fig. 1, are joined together by two cross members, 6 and 7, which may be secured to the said body portions by solder or welding, or may be loosely attached to the body portions by eyes formed on the ends of the members through which the said body portions extend.

In operation the pointed end 4 of the safety pin *a*, is passed through the underneath lining of a dress or other garment at the shoulder of the wearer and fastened within its sheath in the usual manner, while the blunted end 5, of the other safety pin *b* is passed underneath the shoulder strap *c*, forming the usual part of the lingerie or other underwear, and is fastened within its sheath. The two safety pins *a* and *b*, being joined together by members 6 and 7, afford a satisfactory means for preventing the shoulder strap *c* from falling over the shoulders of the wearer, when once the pins are attached to the two garments.

As shown in Fig. 2, the body portions 1 of the two safety pins may be joined together by two vertical members 8 and 9, the latter members being either loosely or rigidly connected to the safety pins as above described.

It is evident that various means may be used to join the two safety pins together such as chains, cloth or strings, and that other means may be substituted for the safety pins, such as clasps, which will satisfactorily hold two separate garments in their proper positions relative to each other.

I therefore do not desire to be confined to the exact forms shown and described, reference being had to the appended claims for the limits my invention may assume.

5 Having described my invention, what I claim is:

1. A device of the class described comprising a pair of safety pins having their

body portions joined together by means of a plurality of crossed members.

2. A device of the class described, comprising a pair of safety pins having their body portions joined together by means of a plurality of crossed members, and a blunted end on one of the safety pins.

ELLEN WEINSTEIN.
